RUBBER SHOE WELTING

Albert Chester Riley, Melrose, Mass., assignor to
 Cambridge Rubber Co., Cambridge, Mass., a
 corporation of Massachusetts

Application December 13, 1937, Serial No. 179,406

2 Claims. (Cl. 36—78)

This invention relates to shoes and other articles of footwear, hereinafter referred to generically as "shoes". It is more especially concerned with rubber shoes and parts thereof.

5 Shoes of this general type as a rule, find their outlet in a lower price class than leather footwear. However, as they have been improved both in their construction and in methods of manufacture, much of the clumsiness and those 10 features which have limited saleability, have been eliminated, and a product has been developed in which those advantages peculiar to this kind of footwear are retained, while still presenting a much better appearance than formerly. The 15 present invention aims to effect further improvements in this direction, and particularly to devise a welt structure suitable for use on extension-edge shoes which will contribute to the attractiveness of these products, and will permit 20 greater variety in design but without adding materially to the expense of manufacture.

The nature of the invention will be readily understood from the following description when read in connection with the accompanying drawing, and the novel features will be particularly pointed out in the appended claims.

In the drawing,

Figure 1 is a perspective view illustrating a step in the preferred method of making applicant's 30 welt;

Fig. 2 is a perspective view of a welt strip;

Fig. 3 is a similar view showing the more commonly used form of welt embodying this invention;

35 Fig. 4 is a perspective view showing the welt applied to a shoe; and

Fig. 5 is a transverse, sectional view of the welt strip shown in Fig. 2.

Referring first to Figs. 2 and 5, the welting 40 there shown comprises a strip 2 preferably made of some rubber composition, or some material which can be handled in a similar manner to mold its surface to the desired configuration, and which will have the necessary toughness, pliability, and other properties essential to a satisfactory welt. Rubber compounds are preferred when the welt is to be used in a rubber shoe because they combine readily with the other elements of the shoe and their characteristics are 45 essentially like those of the parts of the shoe which cooperate with the welt. As shown in the figures just mentioned, the upper surface of the welt has a series of raised elements 3 molded in 50 it and these elements are shaped and arranged

to resemble closely a line of stitches. If desired, the upper surface of the welt also may be corrugated to resemble the wheeling effect or so-called "stitch separating" which is common in leather welts. By making the main body of the 5 welt strip of compositions embodying suitable coloring materials, the welt may be made to suit the requirements of practically any color scheme for a shoe, either blending or contrasting with the shades of adjacent parts, as may be 10 found desirable.

Usually in incorporating such a welt in a rubber shoe, the inner margin of the strip is bevelled, as shown at 4 in Fig. 3. Also, it is usually desirable to have the raised elements 3 which simulate 15 stitches of a color which contrasts agreeably with that of the main body of the welt. This result may conveniently be accomplished by applying a coating of a suitable color to the parts

3. For example, a rubber paint, or one made of 20 any other material compatible with rubber, may be rolled on to the top surfaces of the parts 3. In a dark colored welt such a coating material will naturally be white, and the welt thus will have an appearance substantially like that shown 25 in Figs. 3 and 4. By making these parts 3 project above the adjacent areas of the welt, the application of the coloring material is facilitated and, in addition, the line of stitches is made 30 more prominent.

Thus a welt is produced which contributes materially to the attractiveness and design of a rubber shoe, which can readily be bonded securely to the adjacent portions of the outsole and upper and which adds only a trifling degree to 35 the expense of manufacture of the shoe. Such a welt may also be used in other shoes, particularly those of the cemented type.

According to the method of manufacture at 40 present preferred, a rubber composition of the desired character is made and sheeted. It is then run through a machine equipped with a roll which impresses the desired design in the upper surface of the sheet. Later the sheet is 45 cut along the dotted lines, or in any other convenient manner, to produce welt strips of the desired width. These may be skived along one edge as shown in Fig. 3, or the skiving operation may be performed in connection with cutting the sheet into strips. In making some shoes the welt strip is assembled with the other parts of the shoe while in an unvulcanized condition, but in others the vulcanizing operation is performed prior to such assembly. Thus the prod- 50

uct lends itself to a method of manufacture which can be performed very economically while still producing a thoroughly satisfactory result.

Having thus described my invention, what I desire to claim as new is:

- 5 1. A shoe welt comprising a strip of welt material provided with integral raised elements extending longitudinally thereof and so shaped and arranged as to simulate a line of stitching, and the tops of said raised elements being of a color

contrasting with that of the upper surface of the strip.

2. A shoe welt comprising a strip of welt material provided with integral raised elements extending longitudinally thereof and so shaped and arranged as to simulate a line of stitching, the upper surface of said strip being corrugated, and said raised elements projecting above the adjacent surfaces of the corrugations.

ALBERT CHESTER RILEY. 10
